UNITED STATES PATENT OFFICE

ANDREW ASTRUP AND WILLIAM ASTRUP, OF RACINE, WISCONSIN

HEADLIGHT

Application filed February 4, 1929. Serial No. 337,454.

This invention relates to new and useful improvements in headlights.

One of the objects of our invention is the provision of a novel type of headlight structure wherein there is a continuous passage between the two regular spaced headlights of a motor vehicle with an intermediate light for reflecting rays into the housing of either one of the lights, should anything become wrong with one of the lights and it fails to operate for the purpose disclosed.

Another object of our invention is the provision of a novel type of headlight including novel construction in the connection of the usual spaced headlights whereby the rays from a light positioned between the regular lights will assist in illuminating the housing if one of the regular lights or even both of them should they become useless through the burning of the bulb or any other incidental happening, so that the proper lighting facility for the front end of the vehicle will be provided for.

With the above and other objects in view, the invention consists in the novel features of construction, the combination and arrangement of parts hereinafter more fully set forth, pointed out in the claim and shown in the accompanying drawings wherein:

Figure 1 is a front elevation illustrating a headlight constructed in accordance with our invention;

Figure 2 is a longitudinal section on the line 2—2 of Figure 1;

In the accompanying drawings wherein we have illustrated our improved headlight, we have shown one of the many ways in which the headlight may be supported on the vehicle, but it will be obvious that various types of supporting means can be used in connection with the headlight.

The headlight includes in this construction a centrally disposed arcuate tubular portion 1 enlarged transversely towards its ends so that the end portions provide casings or housings 2 for the regular headlight members 3. The headlight members 3 are provided with the reflecting surface 4 and the usual transparent lenses 5. The light bulb 6 is carried

by the reflector 4 and connected in any suitable manner with the source of supply.

The front wall of the tubular portion 1 is connected to one side of the headlight 3 by the offset part 7 and is provided centrally with an opening 8 normally closed by means of a plate 9, any suitable securing means being used for retaining the plate in place.

In the present instance, we have illustrated screw members 10 extending through the plate 9 and engaging with the front wall of the tubular portion 1.

The rear wall of the tubular portion 1 carries an auxiliary light 11 supported by a socket 12 attached to the rear wall of the tubular portion and the bulb 11 and is connected in any suitable manner to the electrical energy carried by the vehicle.

In order to cause the rays from the bulb or light 11 to be reflected into the reflector portion 4, should the bulb 6 be rendered useless, the reflector portion is provided at one side with an opening 13 leading into a tubular guide member 14 which extends into the tubular portion 1 and is substantially of the same shape at its inner end as the tubular portion, so as to snugly fit therein and present as little obstruction of the rays as possible.

From this it will be apparent that some of the rays of light from the bulb 11 will be cast into the reflector portion 4 and illuminate the interior thereof sufficient to replace the usual light therein to a certain extent. The plate 9 covering the opening 8 may be of any fanciful design upon the front exposed part thereof, and preferably opaque, so as to prevent the greater part of the rays from the bulb 11 from passing therethrough and cause them to be reflected or cast through the reflector portions 4.

The plate, however, if desired, may be transparent so as to clearly illuminate the design thereon.

The tubular portion 1 is preferably arcuate so as to cause the majority of the rays from the bulb 11 to be reflected upwardly and downwardly into the reflector portion 4 when the bulb 11 is lighted and the bulb 6 is out of use, being apparent that a greater amount of light rays will be reflected into the portion 4

with an arcuate shaped tubular part than with a straight tubular part.

As stated heretofore, various ways may be devised for supporting the headlights 3, but in the present instance we have shown standards 15 having their outer ends connected to the fenders 16 of a motor vehicle and disposed at an oblique angle and united or otherwise connected to the housings 2 for supporting the headlights. By retaining the standards 15 in this manner, the standards will have a tendency to brace each other and securely hold the headlights in place.

Attention is directed to the fact that the lines of the tubular portion 1 are such that they readily blend into the contour of regular vehicle headlights and present a neat appearance without any unnecessary projecting parts.

20 The device is extremely useful upon any trips where the bulbs in the usual headlights are likely to be burned out at which time the bulb 11 may be utilized for supplying light to the regular headlights.

25 The device is fairly simple in construction and it is believed that it can be placed on the market at a very low cost, with its usefulness readily appreciated by the motoring public.

30 While we have shown and described the preferred embodiment of our invention, it will be apparent that slight changes may be made in the construction when putting the invention into practice without departing from the spirit of the same or the scope of the

35 appended claim.

We claim:

30 In a headlight structure, a tubular body portion having its ends enlarged transversely to provide housings for headlights, brace members extending laterally from the headlight housings and arranged at an angle out of a parallel with the tubular portion for supporting the tubular portion and the housings in a substantially horizontal plane.

45 In testimony that we claim the foregoing we have hereunto set our hands at Racine, in the county of Racine and State of Wisconsin.

WILLIAM ASTRUP.
ANDREW ASTRUP.
